Benjamin Spieth, Racine, Wis., assignor to
Modine Manufacturing Company, Racine, Wis.,
a corporation of Wisconsin

Application October 29, 1948, Serial No. 149,387

Term of patent 14 years

(Cl. D81—10)

To all whom it may concern:

Be it known that I, Benjamin Spieth, a citizen of the United States, residing at Racine, in the county of Racine and State of Wisconsin, have invented a new, original, and ornamental Design for a Heater Casing, of which the following is a specification, reference being had to the accompanying drawing, forming part thereof.

In the drawing:

Fig. 1 is a perspective view of a heater casing embodying my new design; and

Fig. 2 is a transverse sectional view of the casing illustrated in Fig. 1.

I claim:

The ornamental design for a heater casing, as shown.

BENJAMIN SPIETH.
